(57) **CLAIM**

We claim the ornamental design for a cap, as shown and described.

DESCRIPTION

FIG. 1 is a front elevational view of a cap showing our new design;

FIG. 2 is a rear elevational view thereof;

FIG. 3 is a left side elevational view thereof;

FIG. 4 is a right side elevational view thereof;

FIG. 5 is a top view thereof;

FIG. 6 is a bottom view thereof;

FIG. 7 is an isometric view thereof, looking obliquely into the cap.

FIG. 8 is a front elevational view of a second embodiment;

FIG. 9 is a rear elevational view thereof;

FIG. 10 is a left side elevational view thereof;

FIG. 11 is a right side elevational view thereof;

FIG. 12 is a top view thereof;

FIG. 13 is a bottom view thereof; and,

FIG. 14 is an isometric view thereof, looking obliquely into the cap.
